SPECIFICATION forming part of Design No. 24,392, dated June 11, 1895.

Application filed April 3, 1895. Serial No. 544,342. Term of patent 7 years.

To all whom it may concern:

Be it known that I, JOHN MITTEL, Jr., a citizen of the United States, residing at Chicago, in the county of Cook and State of Illinois, 5 have invented and produced a new and original Design for an Ash-Box; and I do declare the following to be a full, clear, and exact description of the same, reference being had to the accompanying drawings, forming a part 10 thereof.

My invention relates to a design for ash boxes.

In the accompanying drawings, Figure 1 is a perspective view of the box, and Fig. 2 is an 15 end view of the same.

My design comprises and the leading features are, the rectangular base 1, the upwardly

inclined sides 2, the covers 3, arranged at an obtuse angle to the sides, the upper rectangular extension 4 having a cover 5 and the ends 6. 2c

The design is neat and attractive in appearance and is very pleasing to the eye. A box so constructed will be found to have a great deal of space.

What I claim is—
